(57) **CLAIM**

The ornamental design for a waffle plate, as shown and described.

DESCRIPTION

FIG. 1 is a perspective view of the ornamental design for a waffle plate shown with a base;

FIG. 2 is a front view of the ornamental design for a waffle plate shown with a base;

FIG. 3 is a back view of the ornamental design for a waffle plate shown with a base;

FIG. 4 is a left side view of the ornamental design for a waffle plate shown with a base;

FIG. 5 is another side left side view of the ornamental design for a waffle plate shown with a base;

FIG. 6 is a right side view of the ornamental design for a waffle plate shown with a base;

FIG. 7 is another right side view of the ornamental design for a waffle plate shown with a base;

FIG. 8 is a perspective view of the ornamental design for a waffle plate shown without a base;

FIG. 9 is a front view of the ornamental design for a waffle plate shown without a base;

FIG. 10 is a back view of the ornamental design for a waffle plate shown without a base;

FIG. 11 is a right side view of the ornamental design for a waffle plate shown without a base;

FIG. 12 is another right side view of the ornamental design for a waffle plate shown without a base;

FIG. 13 is a top down view of the ornamental design for a waffle plate shown without a base; and,

FIG. 14 is another top down view of the ornamental design for a waffle plate shown without a base.

The broken lines shown throughout the views represent the portions of the design which form no part of the claim.
